PAPER-CARRIAGE FEED MECHANISM FOR TYPE-WRITERS.

984,073.

Specification of Letters Patent. Patented Feb. 14, 1911.

Application filed September 18, 1910. Serial No. 581,859.

To all whom it may concern:

Be it known that I, THEODOR EUGEN BUSCHMANN, a subject of the German Emperor, and residing at Chemnitz, Germany, have invented certain new and useful Improvements in Paper-Carriage Feed Mechanism for Type-Writers, of which the following is a specification.

My invention relates generally to type-writers and a primary object is to provide improved mechanism which enables spaced words to be written without having to strike the space key once or more frequently, after striking a letter key, before the next letter is written.

My invention relates more particularly to a paper carriage feed mechanism for type-writers according to a prior invention, in which a stepping pawl consisting of a single bar is mounted oscillatingly and also longitudinally displaceably on the pawl carrier. This pawl having a twofold movement can be adjusted, according to my invention, in such manner that it cannot at once engage the next tooth of the escapement wheel, but only the following one or the one thereafter. To this end, I connect with the escapement wheel or with the paper carriage a controlling member which controls the pawl and only releases it when two or more teeth have passed by it.

A detent member, whose position is determined by the controlling member and acts on the holding pawl having a twofold movement, coacts with the controlling member. As controlling member I preferably use a notched disk or a star-wheel, with which the detent member, preferably a roller, carried by an angle lever coacts. This detent roller is normally held out of engagement with the controlling member in such manner that it cannot influence the stepping pawl. If the spacing mechanism is to operate, the detent roller is released and lies against the star-wheel. It may then happen, however, that the star-wheel is not correctly positioned relatively to the detent roller so that a letter is first written with the ordinary spacing before the controlling member and the detent roller occupy the correct relative positions in order to influence the pawl for spaced copy.

An important object of my invention is to remedy this defect. I do this by connecting

the star-wheel adjustably with the escapement wheel or with the paper carriage, by mounting the detent roller on a two-part lever, whose two parts are movable to a certain extent relatively to one another, and by subjecting the detent roller to the influence of a spring in such manner that when the spacing mechanism is thrown into gear the detent roller can rotate or shift the controlling member so far that both these parts are situated in the requisite relative positions for typing spaced copy, and accordingly the copy is at once typed spaced.

My new apparatus is very simple in construction and, in addition, it has the further advantage that only one single key requires to be struck once in order to change over from typing ordinary copy to typing spaced copy, and reversely.

The subject-matter of my invention is represented by way of example in the accompanying drawings, wherein:—

Figure 1 is a front elevation and Fig. 2 is a side elevation showing part of a type-writer provided with my improved paper carriage feed mechanism; Figs. 3 and 4 are front elevations showing the parts of the mechanism shown in Fig. 1 in other positions; Fig. 5 is a side elevation of part of the mechanism shown in Fig. 2, but showing the parts in positions opposite to those in that figure; Fig. 6 is a side elevation, showing by way of example, one form of the controlling member applied to the paper carriage; Fig. 7 is a side elevation showing a modified form of my paper carriage feed mechanism, Fig. 8 is a plan of the principal and auxiliary levers employed in this modified form, while Figs. 9 and 9^a show the auxiliary lever in side elevation and plan, respectively, and Figs. 10 to 16 are front elevations showing my feed mechanism in various positions requisite for explaining the mode of operation of the apparatus.

In the construction shown in Figs. 1 to 5, the controlling member has the form of a star-wheel *a* mounted axially at the side of, and rigidly fixed to the escapement wheel *b*. The periphery of this star-wheel is adapted to control a detent roller *c* mounted revolvably on the arm *d* of a three-armed lever *e, d, e*. In the illustrative embodiment the point of each tooth of the star-wheel *a* is situated approximately in the radius of

every second ratchet tooth of the escapement wheel 6. The three-armed lever *c*, *d*, *e* is fulcrumed on a pivot *f* secured in the frame of the machine (Fig. 2) and a pin *d*² on the 5 arm *d* enters into the slot *g*² in the end of the arm *g* of a second three-armed lever *g*, *h*, *i*. A strong tensioned spring *k* connects the arms *h* and *c*. The three-armed lever *g*, *h*, *i* is fulcrumed on a fixed pivot *m*, 10 and its arm *i* rocks within the range of a pin *n* projecting from the side of a stepping pawl 18.

For the purpose of placing this mechanism into and out of operation I connect to 15 one end of the arm *h* a downwardly-directed rod *o*, whose lower end is guided, as shown in Fig. 2, by means of a slot on a fixed pin *p*. A small distance above this slot the rod *o* carries a roller *q* which is adapted to be 20 moved by the operation of a horizontally movable cam-shaped slide *r*. This slide *r* extends toward the front of the typewriter through the front frame plate of the latter where it is formed as a small indicator disk 25 *s*. The cam-slide *r* is operated by means of a pin *t* projecting from it and engaging with a reversing device *u* of known construction which is arranged to be moved from one position into the opposite position by means 30 of a single key *v* each time the latter is depressed. The aforementioned spring *k* is sufficiently powerful to overcome not only the tension of the small spring 18' (Fig. 10) operating the stepping pawl 18, but also to 35 resist both the friction of the entire mechanism comprising levers and other parts designated *a*—*n* and the weight and friction of the rod *o* with its roller *q*.

The above described mechanism operates 40 as follows:—In Fig. 4, to which Fig. 5 appertains, my character spacing mechanism is shown placed out of operation. The roller *q* of the rod *o* is depressed by the projecting part of the cam-slide *r*, and the 45 indicator *s* does not project through the front frame plate of the typewriter. In the position according to Fig. 4 the lever arm *h* is depressed and the lever arm *i* is raised, the stepping pawl 18 being unaffected. The 50 lever arm *g* simultaneously holds its co-operating arm *d* of the other three-armed lever *c*, *d*, *e* in such a position that the detent roller *b* is kept outside the range of influence 55 of the star-wheel *a* in opposition to the pull of the spring *k*.

When it is desired to set the mechanism for spaced matter the key *v* is struck in order to move the cam-slide *r* toward the right in Fig. 5, whereby the recess in the 60 slide is brought under the roller *q* of the rod *o*. The pull of the spring *k* immediately causes the pair of levers *g*, *d* to tilt over toward the left in Fig. 4. This movement 65 brings the detent roller upon the point of a tooth of the star-wheel *a* and the lever arm *i*

upon the pin *n*, without however being able to draw the stepping pawl 18 out of its engagement with the escapement wheel 6 because, owing to the positive coupling of the two three-armed levers by the co-operating pair of lever arms *g*, *d*, the rigid limitation of the movement which the detent roller *b* has found in bearing against the point of the tooth of the star-wheel extends to the lever arm *i*. This position is shown in Fig. 75 3. Now if a letter key be struck, the pawl carrier 12 (Fig. 1) is swung transversely of the teeth of the escapement wheel 6 approximately at right angles to the plane of the drawing, so that the holding pawl 15 80 engages the tooth that is still being held by the stepping pawl 18, whereupon the latter moving sidewise out of the plane of the wheel is caused by the action of its spring 18' to snap into line with the next following 85 tooth space. Then as soon as the tooth is released by the holding pawl on the release of the key, the escapement wheel flies around in the forward direction carrying the star-wheel *a* with it. The detent roller *b* then 90 moves into the following tooth space of the star-wheel, whereby the spring *k* can contract still more and thus depress the lever arm *i* still further. The stepping pawl 18 is not 95 yet engaged by the tooth of the escapement wheel 6, and the depressed lever arm *i* by acting upon the pin *n*, keeps this pawl 18 out of the range of the wheel 6 until the detent roller *b* has moved into the tooth space of the star-wheel. When, however, 100 the point of the star-wheel that follows on next in the direction of rotation begins to pass under the detent roller *b*, the lever arm *i* will be raised to an equal extent, the stepping pawl 18 will be pushed by its spring 105 18' into the range of the teeth of the escapement wheel 6, and then this pawl 18 will engage and retain that tooth of the wheel 6 which lies in the same radius as the point of the next following tooth of the controlling 110 star-wheel *a*. This procedure will be repeated exactly when the next letter key is struck, so that the operation of the controlling wheel *a* shown in Figs. 1 to 4 will produce between every two letters or characters a space equal to the normal spacing 115 of the machine.

In order to produce between every two letters a space equal to two or more times the normal spacing, it is simply necessary to provide a controlling wheel *a* having a correspondingly smaller number of teeth with wider spaces between them.

In the illustrative embodiment shown in Fig. 6 the controlling member acting upon the detent roller *b* has the form of a straight rack, mounted on the paper carriage, with pointed teeth whose pitch will produce the desired spacing greater than normal between the letters and which must be exactly 130

equal to an entire multiple of the single normal spacing of the machine. Consequently, a machine might be rendered capable of writing with two different spacings if it were provided with two systems of lever mechanisms *b*—*v* as described, one of which would be arranged to follow a controlling member in the form of a star-wheel on the escapement wheel 6, while the other would follow a straight rack *w* on the paper carriage. When this spacing mechanism is thrown into gear it can only become immediately operative when the detent roller *b* strikes upon one of the points of the star-shaped controlling member *a*. But as this controlling member is rigidly connected with the escapement wheel 6, when typing a position will frequently obtain, in which the detent roller enters into a space between two points of the controlling wheel *a*. Consequently, the spacing mechanism cannot at once become operative in this event. When typewriting, ordinary spacing will first obtain, and only when the detent roller *b* has passed out of the space between two points of the star-shaped controlling member onto the next point will the spacing mechanism operate uniformly. In other words, as a point and a space of the controlling member *a* in the radii of the teeth of the escapement wheel follow one another alternately, it is clear that the above described spacing mechanism can become operative immediately after it has been thrown into gear only in half the possible positions, while, theoretically speaking, in the other half of the possible positions the first two letters written after the spacing mechanism has been thrown into gear are not spaced, but only separated by the usual space. A further object of my invention is to remedy this defect. In the construction according to Figs. 7 to 16 I attain this end by not connecting the controlling member, *i. e.* the star-wheel, rigidly with the escapement wheel, but allowing it a certain independent movement relatively to the escapement wheel which enables it always to be so placed that, when the spacing mechanism is thrown into gear, the matter is at once typed spaced. This adjustment of the controlling member is brought about by the detent roller. This detent roller is here journaled in an auxiliary lever which is fulcrumed on a principal lever and is under the action of a spring. The end positions of this auxiliary lever are determined by stops or abutments and its connection with the principal lever and the arrangement of said stops are such that, when the spacing mechanism is thrown out of gear, the auxiliary lever rocks in such manner that, when the spacing mechanism is thrown into gear again, it can exercise a pressure on the star-shaped controlling wheel, by which this is brought into the

requisite operative position. The stop limiting the movement of the stepping pawl is influenced in such manner by the principal lever, when the spacing mechanism is thrown into gear, that it permits the pawl to swing a greater angle. The vertical rod connecting the above described key-lever mechanism with the principal lever of the detent roller is also somewhat modified. In this constructional form this rod has an oval hole where it is attached to the principal lever, because when the detent roller runs over the points of the star-shaped controlling member it causes the principal lever to rock, which motion may not of course influence the position of this rod. It is to be noted, in addition, that in the illustrative embodiment of the invention according to Figs. 7 to 16 the above described construction of the mechanism is modified inasmuch as, in consequence of the change in the arrangement and mounting of the detent roller, the latter is not in its operative position when it is on a point of the controlling member, but when it is situated in a space between two points of the same. It is to be understood that my invention is not limited by one definite position in which the detent roller becomes operative.

Referring to Figs. 7 to 16, the axle 5 carries the escapement wheel 6, with which the stepping pawl 18 and the holding pawl 15 engage. The latter pawl is secured on the carrier 12 which also carries the stepping pawl 18, as in the illustrative embodiment according to Fig. 1. The pawl carrier 12 also carries the abutment lever 23; this is pivoted on the pin 24 and is pulled downward by the spring 25 so that its rear arm rests against the pin 26. In this illustrative embodiment of my invention the star-wheel *a* is loose on the axle 5 of the escapement wheel 6. The escapement wheel and the star-wheel are connected by a pawl *a'* which is mounted on the escapement wheel and engages in a ratchet wheel *a*² rigidly connected with the star-wheel. The detent roller *b* is here mounted on an auxiliary lever *e'* fulcrumed on the pivot *f'* carried by the principal lever *g'*. The motion of the auxiliary lever *e'* is limited by the lugs *h'* on the auxiliary lever *e'*. This lever is also under the constant action of a spring *c*² arranged on its pivot *f'*. The principal lever *g'* is fulcrumed at *i'* on the pawl carrier 12 and its shorter arm is attached to a powerful tension spring *k'* which constantly tends to place it so that the detent roller *b* lies against the controlling member *a*. On the end of the longer arm of the principal lever *g'* is a pin *g*³ on which the connecting rod *o'* is suspended by means of its oval hole *m'*. The principal lever *g'* also carries a rod *n'* having a slot surrounding the free end of the abutment lever 23, so that, under certain

circumstances, namely when the principal lever moves upward, the rod n' can influence the lever 23.

The mode of operation of this mechanism will be readily understood from Figs. 10 to 16. In Fig. 10 the spacing mechanism is shown out of operation. The stop 23 for the stepping pawl is situated in its normal position, and when matter is written while the pawl carrier is in the position here shown the stepping pawl 18 can snap forward only one tooth. The machine writes with ordinary spacing. In Fig. 11 the spacing mechanism is shown thrown into gear. The connecting rod o' has moved upward and owing to the principal lever g' having been rocked by the spring k' the detent roller b lies against the star-wheel a . The rod n' has been lifted and has rocked the lever 23 so that the stepping pawl 18 can now snap considerably farther forward and allow one or more teeth of the escapement wheel to pass it without engaging them. Fig. 12 shows the most unfavorable position of the star-wheel. In this position the typed matter would not be spaced the next time a letter-key was struck, but the letters or characters would be written the ordinary distance apart because the detent roller b is just on a point of the star-wheel. The principal lever g' and its rod n' are so positioned by the roller b that they leave the lever 23 uninfluenced. The stepping pawl 18 can allow only one tooth to pass. The star-wheel must be brought from this position, which of course, as mentioned above, frequently occurs in practice, into the correct position; this is done by the detent roller b when the spacing mechanism is thrown into gear. The manner in which the detent roller operates will be understood from Figs. 13 and 14. Fig. 13 shows how the detent roller by running down the inclined face of the tooth of the star-wheel has rotated the latter so far that the pawl a' , coacting with the toothed wheel a^2 connected with the star-wheel a , arrives almost at the next tooth of this ratchet wheel. Fig. 14 shows the subsequent position, in which the spacing mechanism is completely thrown into gear and the star-wheel a correctly set. The lever e' is now thrown over on the lever g' and the detent roller b is at its greatest distance from the fulcrum of the lever g' . Consequently the star-wheel a has rotated so much farther that the pawl a' can fall between the next teeth of the ratchet wheel a^2 . When a letter key is struck and when the escapement wheel rotates, the detent roller b is so influenced by the controlling member a that the stepping pawl 18 omits one tooth, for example, more than usual, so that spaced matter is typed by the machine. Figs. 15 and 16 illustrate the feeding movements in the last described illustrative embodiment

of my invention. In Fig. 15 the pawl carrier 12 is shown swung out at right angles to the plane of the drawing and the stepping pawl 18 is pulled by its spring 18' out of the range of the teeth of the escapement wheel 6. This wheel is retained in this position by the holding pawl 15. As the lever or stop 23 has been thrown over by the principal lever g' by means of the rod n' , the stepping pawl 18 has been able to swing a greater distance and the figure shows that it has not passed by only one tooth, as is usual when writing with ordinary spacing, but two teeth. In Fig. 16 the holding pawl 15 has released the escapement wheel 6 and this can now rotate. As the detent roller b runs on the star-wheel a , it and the principal lever g' are forced downward. Consequently, the stop 23 is released by the rod n' and returns under the influence of its spring 25 into its normal position. It presses against the stepping pawl 18 and drives this into the range of the teeth of the escapement wheel, so that the pawl 18 retains a ratchet tooth determined by the star-wheel a . In the meantime the detent roller b has arrived almost on one of the points of the star-wheel and at the next moment will slide down into the following space in order to prepare for the increased movement of the pawl 18, by rocking the stop 23, so that when the next letter key is struck the pawl 18 will move past two teeth in consequence of its stop 23 being thrown over.

I claim:—

1. In a typewriting machine, the combination with an escapement wheel, of a key-operated pawl-carrier, a holding pawl rigidly mounted on said carrier, a stepping pawl mounted on said carrier for oscillatory and longitudinal movement, means for moving said carrier to cause the pawls to engage the wheel alternately, means for holding the movable pawl out of engagement with said wheel, a controlling member, and a detent roller controlled by said controlling member and actuating said means.

2. In a typewriting machine, the combination with a paper carriage, of an escapement wheel, a key-operated pawl-carrier, a holding pawl rigidly mounted on said carrier, a stepping pawl mounted on said carrier for oscillatory and longitudinal movement, means for moving said carrier to cause the pawls to engage the wheel alternately, means for holding the movable pawl out of engagement with said wheel, a toothed controlling member operatively connected with the paper carriage, and a detent roller controlled by said controlling member and actuating said means.

3. In a typewriting machine, the combination with an escapement wheel of a key-operated pawl-carrier, a holding pawl rigidly mounted on said carrier, a stepping

100

105

110

115

120

125

130

pawl mounted on said carrier for oscillatory and longitudinal movement, means for moving said carrier to cause the pawls to engage the wheel alternately, means for holding the 5 movable pawl out of engagement with said wheel, a revoluble toothed controlling member operatively connected with the escapement wheel, and a detent roller controlled by said controlling member and actuating 10 said means.

4. In a typewriting machine, the combination with an escapement wheel of a key-operated pawl-carrier, a holding pawl rigidly mounted on said carrier, a stepping pawl mounted on said carrier for oscillatory and longitudinal movement, means for moving said carrier to cause the pawls to engage the wheel alternately, a star-wheel operatively connected with the escapement wheel, 15 a detent roller adapted to be controlled by the star-wheel, a pair of spring-pulled counter-levers carrying said detent roller and adapted to move said stepping pawl out of range of the escapement wheel, and lever- 20 actuated means for rocking said levers, causing said detent roller to be driven by the star-wheel and said stepping pawl to be moved out of range of the escapement wheel.

5. In a typewriting machine, the combination with an escapement wheel of a key-operated pawl-carrier, a holding pawl rigidly mounted on said carrier, a stepping pawl mounted on said carrier for oscillatory and longitudinal movement, means for moving said carrier to cause the pawls to engage the wheel alternately, a star-wheel operatively connected with the escapement wheel, a detent roller adapted to be controlled by the star-wheel, means operatively associated 35 with said detent roller and comprising a single key lever for placing the stepping pawl out of range of the escapement wheel and simultaneously causing the detent roller to co-act with the star-wheel, and an indicating member connected with said means for indicating the relative positions of the stepping pawl and the escapement wheel.

6. In a typewriting machine, the combination with an escapement wheel of a key-operated pawl-carrier, a holding pawl rigidly mounted on said carrier, a stepping pawl mounted on said carrier for oscillatory and longitudinal movement, means for moving said carrier to cause the pawls to engage 50 the wheel alternately, a star-wheel having a rim of ratchet teeth coaxial with, and revoluble independently of, the escapement wheel, a detent pivoted on the escapement wheel and engaging in said ratchet teeth, 55 a detent roller running on the periphery of the star-wheel, and means carrying said de-

tent roller for moving said stepping pawl out of range of the escapement wheel.

7. In a typewriting machine, the combination with an escapement wheel of a key-operated pawl-carrier, a holding pawl rigidly mounted on said carrier, a stepping pawl mounted on said carrier for oscillatory and longitudinal movement, means for moving said carrier to cause the pawls to engage the wheel alternately, a star-wheel operatively connected with the escapement wheel, a spring-pulled main lever, an auxiliary lever rocking between limits on the main lever and carrying a detent roller normally coacting with the periphery of the star-wheel, a spring-pulled pivot stop for limiting the rocking movement of said stepping pawl, a rod attached to the main lever and loosely connected to said stop for removing the stop farther from the stepping pawl, a connecting rod pivoted to the main lever for rocking the same against the tension of its spring and thereby removing the detent roller from the star-wheel and permitting the stop to move toward the stepping pawl, and means for reciprocating the connecting-rod.

8. In a typewriting machine, the combination with an escapement wheel of a key-operated pawl-carrier, a holding pawl rigidly mounted on said carrier, a stepping pawl mounted on said carrier for oscillatory and longitudinal movement, means for moving said carrier to cause the pawls to engage the wheel alternately, a star-wheel operatively connected with the escapement wheel, a spring-pulled main lever, an auxiliary lever rocking between limits on the main lever and carrying a detent roller normally coacting with the periphery of the star-wheel, a spring-pulled pivoted stop for limiting the rocking movement of said stepping pawl, a rod attached to the main lever and loosely connected to said stop for removing the stop farther from the stepping pawl, a pin secured on said main lever, a connecting rod having an oval slot slidable on said pin and pivotally connected to the main lever for rocking the same against the tension of its spring and thereby removing the detent roller from the star-wheel and permitting the stop to move toward the stepping pawl, and means for reciprocating the connecting-rod.

In testimony whereof, I affix my signature in the presence of two witnesses.

THEODOR EUGEN BUSCHMANN.
